UNITED STATES PATENT OFFICE.

JOSEPH S. BLINN, OF NEW HAVEN, CONNECTICUT.

DESIGN FOR A CAMPAIGN-BADGE.

SPECIFICATION forming part of Design No. 25,406, dated April 21, 1896.

Application filed February 25, 1896. Serial No. 580,748. Term of patent 3½ years.

To all whom it may concern:

Be it known that I, JOSEPH S. BLINN, of New Haven, in the county of New Haven and State of Connecticut, have invented a new 5 Design for Campaign-Badges; and I do hereby declare the following, when taken in connection with the accompanying drawings and the letters of reference marked thereon, to be a full, clear, and exact description of the same, 10 and which said drawings constitute part of this specification, and represent, in—

Figure 1, a face view of a campaign-badge containing my design; Fig. 2, a side view of the same.

15 This invention relates to a design for campaign-badges; and the design consists in the ornamentation hereinafter described and shown in the accompanying illustration.

The design consists of a button, the face of which is ornamented by the representation 20 of a tom or thomas cat A, a bracket B, and a reed C. As herein shown, the cat is arranged upon the bracket and the bracket arranged above the reed.

I claim—

25 The design for a campaign-badge as herein shown and described.

In testimony whereof I have signed this specification in the presence of two subscribing witnesses.

JOSEPH S. BLINN.
